Attorney.

UNITED STATES PATENT OFFICE.

CHARLES GIBBS, OF NEW YORK, N. Y., ASSIGNOR TO UNDERWOOD TYPEWRITER COMPANY, OF NEW YORK, N. Y., A CORPORATION OF NEW JERSEY.

TYPE-WRITING MACHINE.

975,228.

Specification of Letters Patent.

Patented Nov. 8, 1910.

Application filed January 14, 1910. Serial No. 538,054.

To all whom it may concern:

Be it known that I, CHARLES GIBBS, a citizen of the United States, residing in the borough of Bronx, city of New York, in the county of New York and State of New York, have invented certain new and useful Improvements in Type-Writing Machines, of which the following is a specification.

This invention relates to pressure feed rolls associated with the usual cylindrical platens of writing machines.

A roll or rolls are usually mounted upon a shaft extending parallel with the platen and held in swinging arms controlled by a release key, there being usually two such roll shafts, and separately adjustable springs being usually provided to act upon each shaft.

The object of this invention is the provision of an improved and simplified mechanism to enable the user to regulate the degree of pressure of the rolls without dismantling any portion of the machine, and to maintain a uniform pressure of all the rolls on a shaft.

I mount the springs for a roll or a single series of rolls on a shaft, the turning of which regulates the tension of the springs; and as such springs are of uniform strength, uniformity of pressure is preserved at all variations in the adjustment of the springs. A device carried by the shaft engages a part on the platen frame to maintain the springs under tension.

The outer end of each spring shaft is formed or fitted to be engaged by a rotating key or other tool, whereby the tension may be regulated. Such engagement may be effected without dismantling any part of the machine.

In the accompanying drawings, Figure 1 is a bottom view of the platen frame of an Underwood front strike writing machine, illustrating one embodiment of my invention. Fig. 2 is a cross sectional view of the pressure roll mechanism in normal position. Fig. 3 is a similar view showing the rolls released from the platen. Fig. 4 is a detail view showing the lock for the tension shaft, released.

The platen 1 is usually mounted by an axle 2 in the ends 3, 4 of a platen frame, which are rigidly connected by a rod 5 beneath the platen. Forward and rear pres-

sure rolls 10, 11 are carried by shafts 8, 9 lying parallel with the platen and supported in forwardly and rearwardly extending arms 6, 7, hinged on the rod 5.

To hold the rear roll or rather the series of feed rolls 11 against the platen so that each roll of the series will press against the platen with substantially the same force as every other roll of the series, to effect an even, accurate feed of the paper, springs 15, 16, of uniform strength, are mounted in a manner to press the shaft 9 and its rolls toward the platen; and to enable the operator to regulate the pressure on the entire series of rolls simultaneously, I coil such springs around a tension regulating shaft 13, journaled in bearings 14, one end of each spring being connected to the shaft at 17, the outer ends 18 of the springs pressing against the rearwardly-extending roll-supporting arms 7, 7, located near the opposite ends of the roll-carrying shaft 9. The outer or free ends 18 of the springs exert pressure in the same direction, it being understood that the form of spring may be varied in some cases.

The pressure is regulated by rotating the shaft 13 (see the arrow in Fig. 4). This places both springs 15, 16 under tension and causes their free ends 18 to react against the arms 7, 7, such pressure being transmitted to the shaft 9 to press all the rolls 11 of the series against the platen with approximately equal force.

The shaft 13 is prevented from rotating in the opposite direction by a locking device comprising a stationary crown ratchet 19 engaged by a detent 20, in the shape of a crown ratchet wheel, on the shaft 13.

To enable the operator to readily regulate the pressure of the rolls against the platen, the tension shaft 13 is extended to a point adjacent one end 3 of the platen frame, and may be provided with a ratchet 21 having inclined teeth to be engaged by a key 24, having a similarly toothed bit 25, (see dotted lines in Fig. 4) to wind the shaft to increase the tension. The inclination of the teeth of the ratchet 21 and key 24 prevents strain on the shaft, from an attempt to turn the latter backward, as in such event, the key will slip idly over the teeth of the winding ratchet.

When the shaft is turned by the key 24,

to increase the spring-tension, the detent rides idly over the teeth of the locking ratchet, the shaft 13 moving endwise in its bearings 14 to permit such action, after which the pressure of the tool 24 on the ratchet 21 reengages the detent and locking ratchet, and presses the shaft back endwise.

The tension shaft 13 may be slid endwise in its bearings (see Fig. 4) to disengage the locking mechanism, whereupon the springs will unwind until they have lost their tension, rotating the shaft backwardly; after which the springs may be wound up to a less degree if desired, and the clutch members 19, 20 reengaged to maintain the springs under tension; or the unwinding of the shaft may be controlled by the engagement of the key 24 with the winding ratchet 21 until the tension has been sufficiently reduced.

20 The front pressure rolls 10 are held against the platen in a similar manner by springs 15^a, 16^a mounted on a tension shaft 13^a having a locking ratchet 19^a and detent 10^a, and a ratchet 21^a. The free ends of the 25 springs may engage the roll-carrying shaft 8 to hold it in the downwardly opening slots in the forwardly-extending arms 6, lying behind the tension shaft 13^a. This construction makes the mechanism more compact and locates it closer to the platen and 30 out of the way of other parts of the machine.

The provision of separate tension devices for the respective series of feed rolls, enables the operator to cause one series of feed rolls to press more firmly against the platen than does the other series, if desired.

The pressure rolls may be released by a release key 26 provided upon the end of the 40 platen frame and connected by a link 27 to a crank 28 formed upon a rock-shaft 29 extending along the platen below the rod 5. The rock shaft is provided with flats 30 engaged by release arms 31 connected to the 45 shaft-carrying arms 6, 7.

Having thus described my invention, I claim:

1. In a typewriting machine, the combination with a platen and a plurality of 50 feed rolls, of a spring for urging the feed rolls against the platen, a rotatable tension shaft with which the spring is connected, and a releasable clutch for holding the shaft against accidental rotation.

55 2. In a typewriting machine, the combination with a platen and a feed roll, of a tension device for effecting pressure of the roll against the platen, comprising a rotatable shaft, a spring on the shaft for press- 60 ing the roll against the platen, and a lock for holding the shaft against rotation, the shaft being movable endwise to throw the lock into and out of operation, and having at its outer end a head or part formed to re- 65 ceive a key.

3. In a typewriting machine, the combination with a platen and a series of feed rolls, of a set of springs for effecting a uniform pressure of all the rolls against the platen, a single regulator for controlling the 70 tension of the springs, and a releasable lock for the regulator.

4. In a typewriting machine, the combination with a platen and a series of feed rolls, of a set of springs for effecting a uniform pressure of all the rolls against the platen, a single rotatable shaft with which 75 said springs are connected, and a releasable lock for maintaining the shaft against accidental rotation, to hold the springs at the 80 adjusted tension.

5. In a typewriting machine, the combination with a platen and a series of feed rolls, springs for effecting a uniform pressure of all the rolls against the platen, a 85 shaft with which the springs are connected, the shaft capable of longitudinal as well as rotary movement, a stationary ratchet, and a detent on the shaft meshing with the stationary ratchet to hold the shaft against 90 back rotation and maintain the springs at their adjusted tension.

6. In a typewriting machine, the combination with a platen, a series of feed rolls, and springs for pressing the rolls against the 95 platen, of a shaft with which the springs are connected, means for rotating the shaft in one direction, a stationary ratchet, and a detent carried by the shaft and engaging the ratchet to prevent accidental unwinding of 100 the shaft, and permitting the winding thereof.

7. In a typewriting machine, the combination with a platen frame and a platen, of a series of pressure rolls, springs for pressing 105 the rolls against the platen, a shaft controlling the tension of said springs, a locking ratchet on the frame releasably engaged by a detent mounted upon the tension regulating shaft to permit the shaft to be turned 110 in one direction, and to prevent back rotation thereof, and a ratchet provided on the outer end of the shaft in position to be engaged by a key.

8. In a typewriting machine, the combination with a platen, of a series of paper-feed rolls mounted upon a shaft to coöperate with the platen, casting off and restoring mechanism in which the shaft is loosely mounted, and a spring engaging the shaft 115 and effective to maintain it engaged with the casting off and restoring mechanism and to press the series of rolls against the platen.

9. In a typewriting machine, the combination with a platen and a feed roll, of a tension device for effecting pressure of the roll against the platen, comprising a rotatable shaft, a set of independent springs on the shaft for pressing the roll against the platen, and a lock for holding the shaft 125 130

against rotation; the shaft having at its outer end a head or part formed to receive a key.

10. In a typewriting machine, the combination with a platen and a set of rolls to run thereon, of a movable shaft on which said rolls are mounted, a second shaft having a set of springs thereon, said springs bearing upon said roll-shaft at points between the several rolls thereon, said spring shaft being rotatable to adjust the tension of the springs, and means for detaining said spring shaft where adjusted.

11. In a typewriting machine, the combination with a platen and a platen frame, a rod being supported on said platen frame, of arms pivoted on said rod, a pressure roll carried upon said arms to run upon the platen, and a shaft carrying a spring to press the roll against the platen, said shaft rotatable to adjust the tension of the spring, and extending along the platen, and provided with bearings upon said platen frame, and having a detent.

25. 12. In a typewriting machine, the combi-

nation with a platen and a platen frame, a rod being supported on said platen frame, of two sets of arms pivoted on said rod, a pressure roll carried upon each set of said arms to run upon the platen, and rotatable shafts carrying springs to press the rolls against the platen, each of said shafts rotatable independently of the other to adjust the tension of its spring, a detent being provided for each shaft.

35

13. In a typewriting machine, the combination with a platen and a platen frame, a rod being supported on said platen frame, of two sets of arms pivoted on said rod, a pressure roll carried upon each set of said arms to run upon the platen, and rotatable shafts each carrying a plurality of springs to press the rolls against the platen, each of said shafts rotatable independently of the other to adjust the tension of its springs; 40 a detent being provided for each shaft.

CHARLES GIBBS.
